UNITED STATES PATENT OFFICE.

OSCAR SCHILLER, OF NEW YORK, N. Y.

ORNAMENT FOR LADIES' SLIPPERS.

Application filed January 14, 1924. Serial No. 686,231.

To all whom it may concern:

Be it known that I, OSCAR SCHILLER, a citizen of the United States, residing at New York, in the county of New York and 5 State of New York, have invented certain new and useful Improvements in Ornaments for Ladies' Slippers; and I do declare the following to be a full, clear, and exact description of the invention, such as will enable others skilled in the art to which it 10 appertains to make and use the same.

My invention relates to ornaments used on ladies' slippers and other articles of apparel and it is the principal object of 15 such invention to provide an exceptionally simple and inexpensive device of this class, yet one which will retain its shape and will at all times present an attractive appearance, the device being also of such construction 20 as to permit any accumulated dust to be readily brushed therefrom, whereas such dust cannot be entirely removed from the ordinary pompons now used upon slippers.

With the foregoing in view, the invention resides in the novel subject matter hereinafter described and claimed, the description being supplemented by the accompanying drawing.

Figure 1 is a plan view of a partially 30 completed ornament constructed in accordance with my invention.

Figure 2 is a sectional view on line 2—2 of Fig. 1.

Figure 3 is a bottom plan view of the 35 stiff concavo-convex backing upon which the ornamental covering is secured.

Figure 4 is a sectional view on line 4—4 of Fig. 3.

In the drawing above briefly described, 40 the numeral 1 designates a concavo-convex backing which is preferably of uniform thickness throughout its area being in most instances constructed of cardboard. I have shown the edge portions of the backing 1, 45 formed with openings 2 through which stitches may be passed to secure the device in place, and attention may here be directed to the fact that the concave lower side of the backing permits its edge to tightly engage 50 the article to which it is secured, giving a much better appearance than if portions of such edge were permitted to lie in spaced relation with the article.

Upon the convex upper side of the back- 55 ing 1, I secure a suitable covering of orna-

mental material, and the convex formation imparted to the upper side of the article by the backing 1, gives the appearance of a thick pile or mound of the ornamental material, whereas in reality, the ornamental 60 covering may be rather thin and hence inexpensive.

In the preferred form of construction, I use a length 3 of ornamental braid for covering the backing 1. One end of this 65 braid is passed through a central opening 4 in the backing 1 and is suitably anchored in said opening, for instance, by tying a knot 5 in said end, under the backing. On the convex upper side of this backing, the 70 braid 3 is coiled with its convolutions in sufficiently close relation to effectively cover the backing, and while these convolutions may be secured upon said backing in any suitable manner, they are by preference 75 glued or cemented.

By providing an article constructed in or substantially in the manner shown and described, it may be easily and inexpensively manufactured and sold at small cost, yet 80 it will be very attractive and in every way desirable, particular attention being directed to the fact that the appearance is given of a thick pile or mound of the ornamental material, whereas in reality, only a thin layer 85 may be used; this thin layer permits of the easy removal of any dust which may accumulate thereon, which is greatly advanta- 90 geous over the usual slipper ornaments now in use; and the concave formation of the lower side of the article, allows its edge portion to tightly engage the slipper or other article to which it is attached, thereby giving a better appearance than could otherwise be obtained.

As excellent results may be derived from the details disclosed, these details may well be followed, but within the scope of the invention as claimed, numerous minor changes may be made.

I claim:

1. An ornament for ladies' slippers or other articles comprising a stiff concavo-convex backing, and a covering of ornamental material directly secured upon the convex side of said backing, the convex formation imparted to the upper side of the ornament by said backing serving to give the appearance of a thick pile or mound of the ornamental material, while the concave 105 110

lower side of said backing permits its edge to be held tightly against the slipper or other article.

2. An ornament for ladies' slippers or other articles comprising a stiff concavo-convex backing of circular outline formed with a central opening, and a length of ornamental braid having one end anchored in said opening, said braid being coiled spirally upon and secured to the convex side of said packing.

3. An ornament for ladies' slippers or other articles comprising a stiff concavo-convex backing of circular outline formed with a central opening, a covering of orna-

mental braid for the entire outer face of the convex side of said backing, said covering consisting of a single length of ornamental braid which has one end anchored in said opening by passing said end through the opening and knotting it, the other end of the braid being coiled in a spiral manner from the center of the backing to the periphery thereof, whereby to cover but one side of the backing and permitting the edge of the latter to be held tightly against the slipper.

In testimony whereof I have hereunto affixed my signature.

OSCAR SCHILLER.
